UNITED STATES PATENT OFFICE.

HARRY A. FREDERICK, OF CHICORA, PENNSYLVANIA.

WIRELESS TIE INSULATOR.

Application filed November 18, 1919. Serial No. 338,846.

To all whom it may concern:

Be it known that I, HARRY A. FREDERICK, a citizen of the United States, residing at Chicora, in the county of Butler and State 5 of Pennsylvania, have invented certain new and useful Improvements in Wireless Tie Insulators, of which the following is a specification.

This invention relates to insulators, and a 10 primary object of the invention is to provide an improved insulator for telephones, telegraph or other wires which is so constructed as to eliminate the necessity of employing the usual tie or binding wire.

15 A further object of the invention is the provision of an insulator formed of one piece of insulating material having an improved means for holding or locking a part of the line wire out of direct alignment with 20 the main portion of the wire, whereby slipping of the wire in any direction in relation to the insulator is prevented.

25 A further object of the invention is the provision of means of varying the distance in which the depression of the wire may be moved out of alignment with the main portion of the wire, so that any slack occurring in the wire can be taken up.

30 A still further object of the invention is the provision of an improved means for moving the portion of the wire which is desired to be depressed to locking position, so as to permit the easy and ready placing of the wire in locked position on the insulator.

35 A still further object of the invention is the provision of an improved insulator constructed of a single piece of insulating material, which owing to the novel construction thereof is capable of supporting one or more line wires.

40 A still further object of the invention is the provision of an approved insulator of the above character which is durable and efficient in use, one which is simple and easy to manufacture, and one which can be placed upon the market at a reasonable cost.

45 Other objects will appear in the following detailed description taken in connection 50 with the accompanying drawings, forming a part of this specification, and in which drawings:

55 Figure 1 is a front elevation of the improved insulator showing a conductor wire in operative position.

Figure 2 is a side elevation of the same.

Figure 3 is an enlarged vertical section through the insulator, showing the method of moving the conductor into a locked position.

60 Referring to the drawings in detail, wherein similar reference characters designate corresponding parts throughout the several views, the letter A indicates the improved insulator for supporting the conductor wires B, and including the body C having conductor supporting members D and intermediate locking device E. The means for facilitating the moving of the conductor wire B to locked position is indicated by the letter F.

65 The body C of the insulator is formed of glass or other vitreous material and is substantially conical in configuration and slightly tapered towards its upper end. The 70 lower end of the same is provided with the usual concavity for the reception of the peg 5 carried by the ordinary cross beam of a pole or other support. The body C intermediate its ends is provided with circumferentially extending beads 6 which 75 strengthen the body and prevents breaking thereof during the application of the insulator on the supporting peg.

80 Above the circumferentially extending beads 6 the body C is provided with a supporting arrangement D which includes a pair of spaced brackets 7 formed integrally with or fused on the body. The brackets 7 extend outwardly from the body C and are 85 provided with transversely extending recesses 8 which have the outer walls thereof provided with oppositely directed diagonal 90 slots 9, which communicate with recesses and form means for placing the line wires 95 B in the recesses. Owing to the opposite inclination of the slots 9, the possibility of accidental displacement of the wires B from the recesses is eliminated. As stated the brackets 7 are arranged in pairs and when 100 two wires are to be supported, a pair of brackets is arranged at each side of the body as clearly shown in Figure 2 with its associated parts E and F. Inasmuch as the means for supporting and locking each of 105 the wires B are identically the same in construction, only one of the supporting and locking means for one line wire will be described.

110 The locking means E for the wire B to prevent movement of the same in relation to the brackets include a pair of spaced rack

bars 10 having outwardly and downwardly projecting equi-distantly spaced teeth 11 under which the portion of the wire B lying between the supporting brackets 7 is adapted 5 to be slipped. The lower walls of each of the teeth 11 are provided with areuate notches 12 which form seats for the wire B so as to prevent accidental displacement of the same from the teeth.

- 10 The means E for facilitating the positioning of the wire B under the teeth 11 of the rack bars 10 include a plurality of equi-distantly spaced notches 13 arranged in vertical alignment directly between the rack bars. 15 The notches 13 each include upwardly and inwardly extending inclined faces 14 and horizontally disposed shoulders or rests 15, the purpose of which will be hereinafter more fully described. As clearly shown in 20 Figure 3 of the drawings, the shoulders 15 are in substantially direct alignment with the lower faces 12 of the teeth 11 of the rack bars.

In operation of the improved insulator the 25 line wire B is first inserted in the recesses 8 formed in the brackets 7 by inturning the wire and inserting the same through the slots 9. After the line wire B has been placed in the supporting brackets, the portion of 30 the same lying between the brackets is bent downwardly under any one of the teeth 11 of the rack bars 10 which may be desired. The positioning of the wire B under the teeth 11 of the rack bars is accomplished by 35 using a screw driver 16 or other tool as a lever, and the same is placed over the line wire B with its terminal in engagement with the shoulder or rest 15 of one of the notches 13 which forms a fulcrum seat for the 40 same. The tool 16 is then swung downwardly which pushes the wire into position. The outer faces of the teeth 11 are inclined as at 17 so as to facilitate the sliding of the wire over the same in positioning the wire 45 under the teeth 11 and in the notches 12. The wire B may be moved under any one of the teeth 11 of the rack bars 10 as may be desired so as to effectively take up the slack in the wire.

50 From the foregoing description it can be seen an improved insulator is provided of exceptionally durable construction in which the wire can be readily moved into locked position, and when moved into locked position movement thereof prevented.

55 When it is desired to remove the wire from insulator it is merely necessary to

bring the tool 16 again into play and position the same in engagement with the wire B and one of the notches 13 and move the 60 tool so as to force the wire out of engagement with the rack bars, after which the wire is removed from the brackets in the ordinary manner.

Changes in details such as reversing the 65 position of the teeth 11 and the notches 13 may be made without departing from the spirit or scope of this invention, but:

I claim:

1. An insulator comprising a supporting body having outwardly and longitudinally extending wire supporting brackets formed thereon, and a rack carried by the supporting body substantially parallel with and intermediate said brackets. 70

2. An insulator comprising a body formed of insulating material, outwardly extending wire supporting brackets carried by the body adjacent to the upper end thereof and having transverse recesses formed therein, the outer wall of the brackets having opposite directed diagonal slots communicating with said apertures, and rack bars arranged between the brackets having the teeth thereof arranged to selectively receive the part of 80 the wire lying between the brackets. 85

3. An insulator comprising a body, wire supporting brackets carried by the body having wire receiving openings therein, a rack bar carried by the body intermediate the brackets including a plurality of teeth cooperatively disposed with respect to the openings of said brackets and adapted to selectively receive the wire which extends between said brackets so that said wire may be securely attached to said insulator, and means provided upon said body for receiving a tool to facilitate the placing of a wire upon the teeth of said rack. 95

4. An insulator comprising a body, spaced wire supporting brackets carried by the body provided with wire receiving recesses therein, and a rack intermediate said bracket having a series of teeth therein for selectively receiving that portion of a wire extending between the brackets. 100

5. An insulator comprising a body, a pair of spaced brackets carried by the body, said brackets having transverse apertures formed therein, a pair of spaced rack bars formed on the body and arranged intermediate the brackets, and spaced fulcrum notches arranged intermediate the brackets. 105

HARRY A. FREDERICK.
